DUPLEX STAND

George Abitsch, San Francisco, Calif.

Application October 3, 1934, Serial No. 746,742

3 Claims. (Cl. 248—41)

The invention relates to a duplex stand and more especially to a stand involving separable holders.

The primary object of the invention is the provision of a stand of this character, wherein interfitting parts are separably joined with each other so that one part or both parts when interfitting will support potted plants, a fish bowl or other article for display, and the other part when separated is serviceable as a holder for a Christmas tree, the parts of the stand being interfitting with each other in a novel manner and such parts in their make-up being ornamental for attractiveness.

Another object of the invention is the provision of a stand of this character, wherein the construction thereof is novel in form and the same involves the separable sections or parts, each when separated affording a holder and likewise when interfitting affording an individual stand or holder.

A further object of the invention is the provision of a stand of this character which is extremely simple in its construction, thoroughly reliable and efficient in its purpose, neat and attractive in appearance, strong, durable, readily portable, serving a two-fold purpose and also inexpensive to manufacture.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:

Figure 1 is an elevation of the stand complete and constructed in accordance with the invention, showing supported thereby a potted plant.

Figure 2 is a vertical sectional view showing in detail one part or section separated and supporting a Christmas tree.

Figure 3 is a side elevation of the other part of the stand showing a fish bowl supported thereby.

Figure 4 is a sectional view on the line 4—4 of Figure 1 looking in the direction of the arrows.

Figure 5 is a fragmentary vertical sectional view showing the interfitting parts or sections of the stand with relation to each other.

Figure 6 is a fragmentary perspective view of the interfitting areas of the parts or sections of said stand.

Similar reference characters indicate corresponding parts throughout the several views in the drawings.

Referring to the drawings in detail, the stand comprises separable interfitting parts or sections A and B, respectively, each constituting an independent holder and a single holder when both parts or sections are joined with each other. The part or section A includes a series of standards 10, each formed from a single length metal bar, preferably flat faced, and such bars are disposed in upwardly divergent relation to each other and equidistanted apart from one another. The upper ends of the bars 10 have the outwardly curled terminals 11 and removed from these is an upper ring 12 which is disposed inwardly with respect to the bars 10 and is joined therewith by suitable fasteners 13, the bars 10 above the ring 12 being slightly outwardly flared for accommodating a potted plant 14 which is brought to rest upon the ring 12 and this plant 14 merely exemplifies the stand as a holder for articles to be displaced.

The lower ends of the bars 10 are formed with the outwardly curled terminals 15 which, on the separation of the part or section A from the part or section B, will function as legs or feet for the said section A. The lower portions of the bars 10 have joined therewith the lower ring 16, it being made fast to the said bars by fasteners 17. Thus it will be seen that by the joining of the rings 12 and 16 to the bars 10, a rigid stand is created serviceable for holding articles.

The part or section B, which functions as a base for the part or section A when joined therewith, comprises the series of outside and inside members 18 and 19, respectively, both series having the inwardly curled lower ends 20 and 21, respectively, which function as legs or feet, and these curled ends are joined with each other through rivets or fasteners 22. The outer members 18 have the upwardly converging portions 23 and are made secure to a ring 24, such members 18 and 19 being companions to each other and equally spaced apart, while the inner members 19 have the inwardly curled upper ends 25, these being joined to a ring 26 by rivets or fasteners 27, and thus under this assembly of the said members 18 and 19, rigidity is assured to the section B.

Engaged radially in the ring 24 and threaded therein are winged headed clamping screws 28 having the inner biting ends 29 which, under actuation of the screws, work toward the center 55

of the ring 24 so as to enable a trunk 30 of a tree, serving as a Christmas tree, to be supported and held upright in this section or part B, as is illustrated in Figure 2 of the drawings, when the latter has been separated from the part or section A of the stand.

The ring 16 of the part or section A of the stand has formed therein bayonet slots 31 opening through the lower edge of said ring, and these slots are so located as to accommodate the screws 28 carried by the ring 24, whereby the sections or parts A and B can be interlocked with each other in the interfitting thereof, as is clearly illustrated in Figures 2, 5 and 6 of the drawings, it being understood, of course, that the ring 24 is of a diameter to be accommodated within the ring 16, and in this interfitting of these parts or sections the lower outwardly curled terminals 15 of the part or section A will be seated upon the outer member 18 of the part or section B and, of course, the latter is interlocked with the part or section A when inactive for holding the tree or other article susceptible of being supported by said section or part B.

The screws 28 are turned into the slots 31 for the locking engagement of these parts or sections A and B with each other under interfitting thereof.

In Figure 3 of the drawings the part or section A of the stand is disclosed as supporting in its upper end a fish bowl 32 of any conventional kind. It is, of course, to be understood that the stand is susceptible of holding various articles when the parts or sections A and B are joined

with each other, or when such parts or sections are separated for their individual function as an article holder.

What is claimed is:

1. A stand of the character described comprising duplex article holding sections and adapted for interfitting one with the other, and means for separably locking the sections when interfitted with each other and also functioning for the fastening of an article in one of the sections on the separation of said sections. 5

2. A stand of the character described comprising duplex article holding sections and adapted for interfitting one with the other, means for separably locking the sections when 15 interfitted with each other and also functioning for the fastening of an article in one of the sections on the separation of said sections, and rings carried by the respective sections and one received in the other on the interfitting of the 20 sections.

3. A stand of the character described comprising duplex article holding sections and adapted for interfitting one with the other, means for separably locking the sections when 25 interfitted with each other and also functioning for the fastening of an article in one of the sections on the separation of said sections, and rings carried by the respective sections and one received in the other on the interfitting of the 30 sections, one of the rings being provided with bayonet slots opening through one edge of said ring and removably receiving the locking means.

GEORGE ABITSCH. 35
